UNITED STATES PATENT OFFICE.

ALEXANDER FERDINAND VICTOR, OF ELMIRA, NEW YORK, ASSIGNOR TO WHITE LILY WASHER COMPANY, OF DAVENPORT, IOWA, A CORPORATION OF IOWA.

GEARING.

No. 863,120.

Specification of Letters Patent.

Patented Aug. 13, 1907.

Application filed May 29, 1907. Serial No. 376,396.

To all whom it may concern:

Be it known that I, ALEXANDER FERDINAND VICTOR, a subject of the King of Sweden, and a resident of Elmira, in the county of Chemung and State of New York, have invented certain new and useful Improvements in Gearing, of which the following is a clear, full, and exact description.

My invention relates to improvement in gearing for washing machines, and particularly that for obtaining a rotary reciprocal motion of the stirrer-shaft, set forth in my application for Letters Patent of the United States, filed March 6, 1907, and numbered 360,897.

The object of my invention is to utilize the momentum of a fly-wheel, to assist in the operation of the lever, by which said stirrer-shaft mechanism is actuated. This I accomplish by the means hereinafter fully described and as fully set forth in the claims.

In the drawings:—Figure 1 is a side elevation of a washing tub to which my improvements are applied, showing the portion of the fly-wheel within its rim in dotted lines. Fig. 2 is an elevation of the same, looking at it from a view-point at right angles to that shown in Fig. 1. Fig. 3 is a central vertical section taken on dotted line 3—3, Fig. 1. Fig. 4 is an edge view of the fly-wheel.

In the drawings A represents a circular or other suitably shaped tub, supported by legs, and having a cover B closing its top, that is hinged to the straight edge of a permanent strip b.

30 A vertical stirrer-shaft C is journaled in the center of the cover, having its lower portion, extending into the tub, provided with a suitable stirrer-head (shown in dotted lines in Fig. 2 of the drawings), and the portion above the cover provided with a beveled pinion c, that is engaged by a beveled gear d on the adjacent end of a horizontally disposed drive-shaft D, which latter is journaled in standards secured to and arising from the screw-plate of the supporting-frame a. Shaft D extends beyond the edge of the cover a short distance 35 and is provided with a spur-gear E, the lowest segment of which, when the cover is down, is engaged by a segmental-rack e, that is secured to and made integral with a vertically disposed lever F. Lever F is fulcrumed at its lower end, near the bottom edge of the tub, to a vertically elongated supporting-plate G, which latter, preferably, just below its center of height, is provided with an outwardly projecting bearing-stud g, on which is journaled a fly-wheel H of sufficient diameter, substantially as shown. The inner end of the boss of this 45 fly-wheel is elongated and provided with a pinion h, which is, preferably, integral therewith. Between the top of the tub and said stud g, supporting-plate G is provided with another outwardly projecting bearing-stud j, upon which a large gear J is journaled. This 50 gear is actuated by the lever F, and is adapted to en-

gage the pinion h and revolve the fly-wheel at a comparatively high speed. In order to enable said lever to actuate gear J, I provide the lever with a vertically elongated slot k, and provide gear J with a wrist-pin K, which projects outwardly from one of its arms, 60 through the said slot k. The slot k is of a length corresponding to the diameter of the perimeter of the wrist-pin, and as said lever is moved back and forth it, through the medium of said wrist-pin, revolves the gear J. In order to avoid interference with pinion h, 65 I provide the lever, below said slot, with a transversely elongated open frame M. The longitudinal sides of this frame are, preferably, struck from the center of the fulcrum of the lever, and are sufficiently far apart to clear the said pinion h as the lever is moved back and 70 forth.

The operation of my invention is such that when the lever F is operated, its reciprocations will be limited by the wrist-pin K, and the likelihood of the wrist-pin getting in such position that, when at rest, it will be 75 impossible to move the lever, is very remote, because the momentum of the fly-wheel will, when the lever is released, carry the said wrist-pin past the position of the gear where a dead center is likely to occur.

What I claim as new is:—

1. In a mechanical movement for washing machines, a vertical rotary reciprocal stirrer-shaft, a rotary reciprocal drive-shaft the axis of which is at an angle thereto, and a pinion at the end thereof opposite said stirrer-shaft, in combination with a vertically disposed lever of the second class, a segmental-rack carried thereby and engaging said pinion, a fly-wheel the axis of which is parallel to that of said drive-shaft and means for transmitting the motion of said lever to said fly-wheel. 80

2. In a mechanical movement for washing machines, a vertical rotary stirrer-shaft, and a horizontally disposed drive-shaft connected to the same, in combination with a vertically disposed lever of the second class actuating said drive-shaft, a fly-wheel the axis of which is parallel to that of said drive-shaft, and means for transmitting the motion of said lever to said fly-wheel. 90

3. In a mechanical movement for washing machines, a vertical rotary reciprocal stirrer-shaft, a rotary reciprocal drive-shaft, the axis of which is at an angle thereto, and a pinion at the end thereof opposite said stirrer-shaft, in combination with a vertically disposed lever of the second class, a segmental-rack carried thereby and engaging said pinion, a fly-wheel the axis of which is parallel to that of said drive-shaft, and a gear the axis of which is parallel to that of said fly-wheel for transmitting the motion of 100 said lever to said fly-wheel.

4. In a mechanical movement for washing machines, a vertical rotary stirrer-shaft, and a horizontally disposed drive-shaft connected to the same, in combination with a vertically disposed lever of the second class actuating said drive-shaft, a fly-wheel the axis of which is parallel to that of said drive-shaft, a gear the axis of which is parallel to that of said fly-wheel for transmitting the motion of 110 said lever to said fly-wheel.

5. In a mechanical movement for washing machines, a vertical rotary reciprocal stirrer-shaft, a rotary reciprocal drive-shaft the axis of which is at an angle thereto, and a 115

pinion at the end thereof opposite said stirrer-shaft, in combination with a vertically disposed lever of the second class, a segmental rack carried thereby and engaging said pinion, a fly-wheel the axis of which is parallel to that of said drive-shaft, a gear the axis of which is parallel to that of said fly-wheel and drive-shaft and located mediate the same for transmitting the motion of said lever to said fly-wheel.

6. In a mechanical movement for washing machines, a vertical rotary reciprocal stirrer-shaft, and a horizontal rotary reciprocal drive-shaft engaging the same, in combination with a vertically disposed lever for actuating said drive-shaft having a longitudinal slot therein, a fly-wheel having a wrist-pin engaging said slot the axis of which is parallel to said drive-shaft and mediate the same and the fulcrum of said lever, a gear revolved by said lever the axis of which is parallel to and between the axes of said drive-shaft and fly-wheel to which latter it transmits motion.

10 7. In a mechanical movement for washing machines, a vertical rotary reciprocal stirrer-shaft, and a horizontal rotary reciprocal drive-shaft engaging the same, in combination with vertically disposed lever for actuating said drive-shaft, a fly-wheel the axis of which is parallel to said drive-shaft and mediate the same and the fulcrum of said lever, a gear revolved by said lever the axis of which is parallel to and between the axes of said drive-shaft and fly-wheel to which latter it transmits motion.

15 8. In a mechanical movement for washing machines, a vertical rotary reciprocal stirrer-shaft, and a horizontal rotary reciprocal drive-shaft engaging the same, in combination with a vertically disposed lever for actuating said drive-shaft, a fly-wheel the axis of which is parallel to said drive-shaft and in the same vertical plane therewith and

mediate the same and the fulcrum of said lever, a gear revolved by said lever, the axis of which is parallel to and between the axes of said drive-shaft and fly-wheel to which latter it transmits motion.

9. In a mechanical movement for washing machines a vertical rotary reciprocal stirrer-shaft, and a horizontal rotary reciprocal drive-shaft engaging the same, in combination with a vertically disposed lever for actuating said drive-shaft having a transversely elongated opening therein, a fly-wheel the axis of which is parallel to said drive-shaft and extends out through said opening mediate the axis of the drive-shaft and the fulcrum of said lever, a gear revolved by said lever, the axis of which is parallel to and between the axes of said drive-shaft and fly-wheel to which latter it transmits motion.

10 10. In a mechanical movement for washing machines, a vertical rotary reciprocal stirrer-shaft, and a horizontal rotary reciprocal drive-shaft engaging the same, in combination with a vertically disposed lever which actuates said drive-shaft, and has a longitudinal slot therein, and a transversely elongated opening below said slot, a fly-wheel having a wrist-pin engaging said slot the axis of which extends through said transverse opening, is parallel to said drive-shaft and mediate the same and the fulcrum of said lever, a gear revolved by said lever the axis of which is parallel to and between the axes of said drive-shaft and fly-wheel to which latter it transmits motion.

In testimony whereof I have hereunto set my hand and seal this 15th day of April, A. D. 1907.

ALEXANDER FERDINAND VICTOR. [L. S.]
